H. J. BROWN

TRUNK HATBOX

Filed May 13, 1921

Fig. 2

INVENTOR
HARRY J. BROWN

BY
Philip S. McLean
ATTORNEY

UNITED STATES PATENT OFFICE.

HARRY J. BROWN, OF MONTREAL, CANADA.

TRUNK HATBOX.

Application filed May 13, 1921. Serial No. 469,129.

To all whom it may concern:

Be it known that I, HARRY J. BROWN, a subject of the King of Great Britain, and a resident of Montreal, Canada, have invented certain new and useful Improvements in Trunk Hatboxes, of which the following is a specification.

The objects of this invention are to provide a folding hat box which can be set up 10 in an ordinary trunk and which, when not in actual use, may be folded or collapsed and stored in flat condition.

The invention also aims to provide a device of this nature which will be relatively 15 simple and inexpensive and which will be strong and durable so as to thoroughly protect the hats and so as to withstand the usage and handling to which such devices are subjected.

20 A further important object is to make the device readily attachable to and detachable from the ordinary trunk.

In the attainment of these objects, I have devised certain novel features of construction, combinations and arrangements of parts, all of which will appear from the following specification which is to be read in conjunction with the accompanying drawing forming part hereof and wherein I have 30 disclosed the invention embodied in one of its simplest and most practical forms.

Figure 1 in the drawing is a perspective view of the device as assembled and set up in the corner of a trunk, the walls and cover 35 of the trunk being broken away and appearing partly in section.

Figure 2 is a plan view of the structure in its folded form.

Figure 3 is a detail of the two parts of the 40 box in separated relation.

In the form herein disclosed, the body of the box is of rectangular shape comprising the four side walls 5, 6, 7 and 8, hingedly connected together at the corners at 9 so that 45 they may fold into flat form, as shown in Figures 2 and 3. These walls may be made up of heavy cardboard, for instance, covered by a suitable fabric which may of itself provide the flexible hinges for the corners 9.

50 This box form is usually set up in a corner of the trunk, as shown in Figure 1, with the wall 8, for instance, resting against an end wall 10 of the trunk, and the wall 7 resting against the back wall 11 of the trunk, and all four walls bearing at their lower 55 edges on the bottom 12 of the trunk. The

collapsible walls are suitably secured in this relation, in the illustration, by straps 13 and 14 fastened at 15 and 16 to the end and rear wall of the trunk and detachably connected with the end and side walls 5 and 6 of the box as by means of snap or so-called glove fastenings 17. It will be evident that when these fastenings are engaged, the box will be firmly secured in the corner of the trunk 60 and will be rigidly braced by the corner walls of the trunk. If desired, also, I may provide one or more strap fastenings 18 for securing one or more of the collapsible walls of the box to the bottom of the trunk. 70

This construction enables me to quickly secure the box in operative position within the corner of the trunk and at the same time enables the box to be readily detached from the trunk walls and to be flattened out for 75 shipment or storage.

The various securing straps are preferably fastened to the trunk walls, as I have shown, that is, in back of or concealed behind the box walls. This enables such fastenings to 80 draw and hold the assembled box more firmly in its corner.

Applied over the upper edges of the box wall there is usually provided a top 19 which likewise is detachably secured in place, for 85 instance, by straps 20 at the four sides thereof, said straps being secured, as indicated at 21, to the lower side of such top and having snap fastenings 22 for detachably engaging the top to the four side walls. 90 The portions of such straps which lie at the under side of the top may seat in notches 23 provided in the upper edges of the box sides. This serves to position the top accurately on the side walls and exerts a certain bracing 95 effect tending to overcome any collapsing pressure which may be applied to the box.

The top is shown as provided with an opening 24 therein to receive the crown of the hat, and the side walls are indicated as 100 having a certain curvature at 25 approximately the curvature of an ordinary hat-brim. This enables the hat to fit with the brim resting snugly on the top 19 which ordinarily will flex to fit the curved edges 105 of the side walls 6 and 8. This flexure of the top also, it will be observed, is effective in bracing the box against collapsing forces.

The straps at the sides of the top are shown as provided with upward extensions 110 26 and 27 which may be brought together over the hat seated in the opening 24, these

straps being adjustably caught together, for instance, by a buckle fastening 28.

The fastenings by which the folding box is secured in the trunk are preferably of such form or so constructed that they may be readily applied to the trunk walls. They may, for instance, be in the form of small leather tabs carrying glove fastener elements and adapted to be secured in place by 10 means of suitable easily applied securing devices. When the hinged box walls are folded flat, they may be secured in this relation and at the same time the top may be fastened thereto, by locating said top at 15 the back and securing the straps 26, 27 across the face of the foldable member, as shown in Figure 2. This makes a very compact flat bundle which may either be carried in the trunk or stored elsewhere.

20 What I claim is:

1. An open bottom collapsible hat box having four side walls hingedly connected at the ends to thereby enable such side walls to be folded flat against one another and to 25 be opened up into box-like form, said box having means for securing the walls in this expanded box-like form when the box is thus set up with two of its side walls backed against the corner walls of a trunk and resting with its lower edges on the bottom of 30 the trunk so that said bottom of the trunk will then provide a bottom for the box.
2. An open bottom collapsible hat box having four side walls hingedly connected 35 at the ends to thereby enable such side walls to be folded flat against one another and to be opened up into box-like form, said box having means for securing the walls in this expanded box-like form when the box is thus set up with two of its side walls backed against the corner walls of a trunk and resting with its lower edges on the 40 bottom of the trunk so that said bottom of

the trunk will then provide a bottom for the box and a top for the collapsible box 45 of the approximate outline of the side walls in their extended relation, said top having a seat for a hat and having means for detachably securing the same to the side walls so as to thereby assist in holding the collapsible walls in their extended relation. 50

3. A collapsible hat box having side walls so connected at their ends as to enable their being folded flat together and to be set up in box-like form in the corner of a trunk 55 with such side walls bearing against the corner walls of the trunk and sustained on the bottom of the trunk and means for detachably and releasably securing and confining the box walls sustained in this set up 60 relation in the corner of a trunk, ready to receive a hat and in condition to be quickly collapsed and folded flat for storage within the trunk.

4. The structure of claim 3 with a top detachably engageable over the side walls and having cooperating positioning elements to assist in holding the side walls in their standing set up relation. 65

5. A hat box having collapsible side walls 70 which can be extended to form a box-like enclosure in the corner of a trunk, means for detachably and releasably securing and confining the thus extended box walls sustained in the set-up relation in the corner 75 of a trunk, a top for holding a hat, conforming in shape to the extended box-like form and adapted to rest and be supported at the upper edges of the side walls and means for positioning and detachably securing the top thus detachably sustained 80 by the side walls.

In witness whereof, I have hereunto set my hand this 9th day of May, 1921.

H. J. BROWN.
